Sweden, assignor to Telefonaktiebolaget L. M.
Ericsson, Stockholm, Sweden, a company of
Sweden

Application May 26, 1933, Serial No. 673,057
In Germany June 6, 1932

3 Claims. (Cl. 179—17)

The present invention relates to such signaling and telephone systems in which a plurality of subscribers' positions are connected to a common double line or party line and in which calls 5 are effected discriminately through the actuation of selectors disposed at the subscribers' positions.

In such systems it has proved to be of advantage to use one source of current for calls and dialled impulses and another source of current 10 for setting of the selectors, it being hereby avoided to have the line when at rest under a voltage of the order of magnitude required to render possible the operation of a plurality of distributed 15 selectors. In known arrangements of this kind there has either been provided an extra circuit by means of earthing the apparatus, or two different kinds of currents have been used, viz. alternating current and direct current. It is, however, particularly in railway telephony in connection with electrified railways, a disadvantage 20 to use earthing, due to the danger of getting overvoltages to earth, and the use of alternating current along with direct current has involved such difficulties in connection with the setting of the 25 selectors simultaneously with the occurrence of the dialled impulses that registers have had to be provided. The present invention renders possible the use of two sources of direct current without earthing the apparatus and without using 30 registers.

According to the present invention this is rendered possible thereby that the impulse sending and impulse receiving circuits at the subscriber's position are connected as separate circuits, yet in 35 parallel with each other and in series with current blocking devices, in such a manner to the double line that said impulse circuits together with the switching means of a controlling arrangement common to the double line form direct 40 current circuits which are closed over said double line.

The present invention will now be described with reference to the accompanying drawing, in which Figure 1 shows in principle a switching 45 arrangement for a party line and Figure 2 a detailed diagram for a subscriber's set.

In the switching arrangement shown in Figure 1 GL is the common double line or party line along which the different subscribers' positions 50 A₁, A₂ are distributed. For the setting up of talking connections there is provided a relay set R₁ to R₃ common to all subscribers' positions. In the subscribers' positions the driving magnet SM of the selector and the dial F are connected in 55 parallel to the party line GL. Further, the driv-

ing magnet SM and the dial F are each connected in series with an appertaining rectifier L₁ and L₂ respectively, for example a cuprous oxide rectifier. In relation to the polarity of the line GL said rectifiers are turned in opposite directions. The driving magnet SM is permanently connected to the line GL through a rectifier L₁ said rectifier being so turned, however, that it does not pass any current at the normal condition of voltage between the two branches of the line GL. Neither can any current pass over the circuit extending through the dial F for the reason that said circuit is interrupted at a contact 1 of the switch hook KL. The selectors are assumed to be of the type the wipers of which are advanced one step for each current impulse. A suitable type of selector is described in my copending application No. 29,957. The said selector is a rotary selector which stops in the position at which it has come when the impulsive current ceases. Another type which may be used is a two-magnet selector in which both magnets are inserted in the impulse-circuit. One of the magnets is arranged to actuate an armature fitted with a ratchet, the ratchet wheel being moved one step when the armature is attracted. The other magnet moves a ratchet which prevents the ratchet wheel moving backwards when the magnet is energized. When both armatures are in rest position the ratchet wheel is returned to home position by a spiral spring similar to the escapement spring of a clock. When the ratchet wheel is in certain positions a contact is closed, as the armature of the stepping magnet lifts a contact spring towards the movable contact arms. The number of steps from the home position to the position of the ratchet wheel when this closing occurs corresponds to the calling number of the telephone to which the selector in question belongs. To the common line GL may, of course, be connected 40 an arbitrary number of subscribers' positions A. In the arrangement shown on the drawing it has been assumed that nine subscribers' positions are connected to the line GL, each subscriber's position corresponding to one contact position on the selectors. If the line GL is connected to a telephone exchange the selectors are also provided with a contact position for calls to the telephone exchange in which position a selector is connected to the line GL.

The setting up of a talking connection between two subscribers A₁ and A₂ connected to the line GL will now be described. When the subscriber A₁ lifts his microtelephone the switch hook KL closes a contact 1, a circuit 2 being then formed

through the dial F and two windings RL₁ and RL₂ of a relay R₁ in the common relay set. The relay R₁ operates and closes at its contact 3 a circuit for a relay R₂ which in turn closes a circuit 5 for a relay R₃. When the latter relay operates it interrupts at its contact 4 the circuit through the relay R₂, at the same time locking itself at its contact 5. During the short interval of time when the relay R₂ is energized it causes interruption of the circuit 2 and connects via its contacts 6,7 in such a manner a current source to the line GL that the potential on the line is reversed. The driving magnets SM of all selectors connected to the line will then be actuated by a current 10 pulse, the wipers of the selectors being then advanced one step from their home positions. The current source which by means of the relay R₂ is connected to the line GL must as mentioned before have a voltage sufficient for the operation 15 of the selectors. Said source of current may of course, if conditions permit, be the same source of current as is connected to the line GL through the relay R₁. When the relay R₂ is energized and the circuit 2 is closed the relay R₁ will maintain 20 its armature attracted on account of its winding RL₁ being included in a circuit through a resistance r and the contact 6 of the relay R₂. Through the advancing of the wipers of the selectors taking place in consequence of the call 25 optically busying of the party line at the subscribers' positions not involved in the connection may be obtained if the selector is arranged to operate a flatter or the like immediately upon leaving of the home or normal position. When the subscriber 30 A₁ dials the wanted number on his dial F a number of interruptions are effected in the circuit 2. For each such interruption the relay R₁ opens its contact 3 for a moment, an interruption being 35 then caused in the circuit of the relay R₃ which immediately releases. When after a moment the relay R₁ again closes the contact 3 a circuit is formed in the same manner as described above 40 for the relay R₃ which locks itself and interrupts the circuit through the relay R₂. During this 45 period of time the relay R₂ has caused the sending of a current impulse over the line GL, all driving magnets SM connected to the line having then been actuated. Consequently, each interruption in the circuit 2 causes the advancing of the 50 wipers of the corresponding selectors one step. In case the subscriber A₁ dialled number nine, hereby causing nine current interruptions, the wipers will be advanced nine steps. Ringing signal is 55 then effected at the connected subscriber's station A₉, for instance, thereby that a special wiper of the selector K₁ in Fig. 2 in the connecting position 8 in Fig. 2 of the selector closes a local galvanic circuit for a ringer B in Fig. 2. When the latter lifts his microtelephone the talking 60 connection is completed. The current impulses sent over the line GL by the relay R₂ have a duration which is exclusively dependent on the manner of operation of the relays R₂ and R₃ and independent of the impulse ratio of the dial. In this manner there is obtained with simple means an impulse correction which may be of advantage, particularly in traffic between different systems.

In the switching operation now described current impulses are sent by the relay R₂ as soon as the relay R₁ on account of the closing of the circuit 2 attracts its armature. It is, of course, also conceivable to arrange the circuits so that current impulses are sent over the line GL by the relay 70 R₂ when the relay R₁ releases on account of an

interruption at the dial F in the circuit 2. This may be obtained, for example, by designing the contact 3 of the relay R₁ as a resting contact. As in such a case the circuit extending through the dial F of the calling subscriber will be interrupted during the sending of the current impulses to the driving magnets SM, the rectifier L₂ may be dispensed with. 5

At a call from the subscriber A₁ to a subscriber which is not connected to the party line GL the 10 subscriber A₁ first dials a special number of impulses, for example ten, whereby connection to the telephone exchange to which the line GL is connected is obtained, for instance, by means of a selector of the same type as those which are 15 arranged at the subscribers' positions. Thereupon the subscriber A₁ dials the wanted number, the talking connection being then set up in the same manner as if the subscriber A₁ had been an ordinary subscriber belonging to the telephone 20 exchange in question.

When upon completion of the conversation the calling subscriber A₁ rehooks his microtelephone the circuit 2 is interrupted at the contact 1 and a 25 relay R₁ is deenergized as is also the relay R₃. Upon completion of the conversation all selectors should be restored to their home positions. This can be effected in known manner either mechanically by means of spring power or by letting each selector operate as a self-acting step 30 35 selector until it reaches its home position. Through a special arrangement of a rectifier in parallel with the driving magnet the selectors may, however, be restored in a simple manner by means of impulses sent over the line GL. The arrangement herefore will be more closely described in connection with the apparatus construction shown in Figure 2.

In the subscriber's apparatus shown in Figure 2 the microphone M is fed from a local battery for the reason that battery supply from the exchange battery can become very varying on account of the different line resistances occurring between the exchange and the subscribers' sets on the same line. The telephone receiver T as well as the microphone M is inductively connected to the party line GL through an induction coil IR having three windings. In addition the apparatus contain an ordinary dial F, a switch hook KL, a trembler bell B, and a selector set consisting of a selector S with appertaining driving magnet SM and three rectifiers L₁, L₂, L₃. The selector S has two different wipers K₁, K₂. One wiper K₁ brings about the joining up of the bell B in a local circuit through the switch hook KL, and the other wiper K₂ connects in its last position a rectifier L₃ in parallel with the driving magnet SM which hereby becomes slow-acting. If the selectors along the line GL are restored in known manner by means of a train of impulses sent over the line GL the wipers of the selectors will first be advanced step by step to the last contact position in which the wipers remain until the train of impulses has ceased when they are moved to the first position. Consequently, said arrangement with a rectifier connected in parallel with the driving magnet in the first position renders possible the sending upon each clearing signal of a train of impulses containing a constant number of impulses. This number is so determined 60 65 that all selectors are certainly restored to their home positions also if one impulse or another should not actuate a certain individual selector or if for some reason the wipers of the selectors 70 75

should not occupy the same position at the beginning of the clearing. In the shown construction of the subscriber's set the bell B is put into circuit by the wiper K via a contact position 8 5 corresponding to the number of the set and also via another contact position 9 common to all sets and being used at a simultaneous call to the sets along the line GL.

In the example shown on the drawing the driving magnets SM are connected in series with rectifiers L₁ preventing current from passing through the driving magnets at the voltage condition normally existing between the two branches of the line GL. Provided that a higher voltage 10 than the normal one is used for operating the selectors said selectors may be substituted by glow discharge tubes which are then so selected that they do not pass any current at the voltage used during calls and impulse sending from the 15 dial. When the voltage thereafter is raised during the sending of current impulses to the driving magnets the glow discharge tubes will pass current and the driving magnets may be actuated. As in the latter case the voltage between 20 the line branches is reversed no current will pass through the dials.

I claim:—

1. In a telephone system a two wire party line, a number of telephone stations connected thereto, a controlling arrangement connected to the line and common to the said stations, an impulse sending and an impulse receiving circuit at each of the said stations connected to the double line in parallel with each other, step-by-step switches 30 in the said impulse receiving circuits, and impulse senders in said impulse sending circuits, a rectifier inserted in each impulse receiving circuit, and a rectifier inserted in each impulse sending circuit, the said rectifiers being directed so that the said impulse circuits together with the 35 said controlling arrangement form direct current circuits of opposite directions over the common two wire party line and switching means in the common controlling arrangement allowing a continuous stepping of the different step-by-step switches from an impulse sending circuit during the impulse sending.

2. In a telephone system a two wire party line, a number of telephone stations connected thereto, a controlling arrangement connected to the line and common to the said stations, an impulse sending and an impulse receiving circuit at each 5 of the said stations connected to the double line in parallel with each other, step-by-step switches in the said impulse receiving circuits, and impulse senders in said impulse sending circuits, a rectifier inserted in each impulse receiving circuit and 10 a rectifier inserted in each impulse sending circuit, the said rectifiers being directed so that the said impulse circuits together with the said controlling arrangement form direct current circuits of opposite directions over the common two 15 wire party line, switching means in the common controlling arrangement allowing a continuous stepping of the different step-by-step switches from an impulse sending circuit during the impulse sending and a further rectifier which is connected to the last contact position of the step-by-step switch so as to form a shunt to the same.

3. In a telephone system a two wire party line, a number of telephone stations connected thereto, a controlling arrangement connected to the 25 line and common to the said stations, an impulse sending and an impulse receiving circuit at each of the said stations connected to the double line in parallel with each other, step-by-step switches in the said impulse receiving circuits, and impulse 30 senders in said impulse sending circuits, a rectifier inserted in each impulse receiving circuit and a rectifier inserted in each impulse sending circuit, the said rectifiers being directed so that the 35 said impulse circuits together with the said controlling arrangement form direct current circuits of opposite directions over the common two wire party line, switching means in the common controlling arrangement allowing a continuous stepping of the different step-by-step switches from 40 an impulse sending circuit during the impulse sending and a relay set at the controlling arrangement which sends impulses to the step-by-step switches which are independent of the impulse ratio of the dial.

HARALD VALDEMAR ALEXANDERSSON.
